AMPHIBIAN

Louis Csicsko, Brooklyn, N. Y.

Application March 2, 1956, Serial No. 40,437

Term of patent 3½ years

(Cl. D71—1)

Figure 1 is a top-plan view of an amphibian embodying my new design with the wheels in retracted position;
Figure 2 is a side elevational view of Figure 1;
Figure 3 is a bottom plan view of Figure 2;
Figure 4 is a rear elevational view of Figure 2;
Figure 5 is a front elevational view thereof;
Figure 6 is a front elevational view of Figure 2 with the wheels extended;
Figure 7 is a perspective view of the amphibian which embodies my new design.

I claim:
The ornamental design for an amphibian as shown.
